UNITED STATES PATENT OFFICE.

GEORGE W. MCGILL, OF NEW YORK, N. Y.

DESIGN FOR A BOX.

SPECIFICATION forming part of Design No. 22,701, dated August 15, 1893.

Application filed July 12, 1893. Serial No. 480,309. Term of patent 14 years.

To all whom it may concern:

Be it known that I, GEORGE W. MCGILL, a citizen of the United States, residing at Riverdale, (New York,) in the county of New York and State of New York, have invented or produced a new and original Design for Boxes, of which the following is a specification.

This design has for its object to provide a novel and ornamental box, which presents a 10 handsome, distinguishing, and characteristic appearance to the eye; and it consists in a box having top and bottom raised surfaces or disks, a surrounding band of greater diameter than the raised surfaces or disks, and 15 curved or arched ribs or flutes interposed between the surrounding band and the top and bottom raised surfaces or disks.

The design is illustrated by the accompanying drawings, in which—
20 Figure 1 is a plan view of a box constructed in accordance with my design; and Fig. 2 is a perspective view of the same.

In the drawings the numerals 1 and 2 indicate the top and bottom raised surfaces or disks, which may have their edges milled, as 25 at 3 and 4; and the numeral 5 indicates the

centrally arranged annular or surrounding band of considerably greater diameter than the raised surfaces or disks. The numeral 6 indicates a dividing line directly above an 30 annular milled bead 7, by which the box is converted into upper and lower sections. The annular or surrounding band 5 may be perfectly plain, and it is connected with the top 35 raised surface or disk 1 through the medium of curved or arched ribs or flutes 8, and with the lower raised surface or disk 2 through the medium of curved or arched ribs or flutes 9.

The design provides a novel box which is ornamental and handsome, and presents a 40 distinguishing appearance.

What I claim is—

The design for a box, substantially as herein shown and described.

In testimony whereof I have hereunto set 45 my hand in presence of two subscribing witnesses.

GEORGE W. MCGILL.
